ABSTRACT

High purity C₈ aromatic hydrocarbons are produced by prefractionating a C₈-400° F. naphtha feed fraction into a 270° F. to 275° F. endpoint fraction and catalytically reforming this 270° F. to 275° F. endpoint fraction to produce a reformate having a minimum of C₈+ hydrocarbons. The reformate is then passed to a deoctanizing zone and a rerun column zone to recover a mixture of high-purity C₈ aromatic hydrocarbons.

PROCESS FOR PRODUCING A MIXTURE OF HIGH-PURITY C₈ AROMATIC HYDROCARBONS

BACKGROUND OF THE INVENTION

This invention relates to a process for producing a mixture of high purity C₈ aromatic hydrocarbons. It particularly relates to a process for producing a mixture of high-purity C₈ aromatic hydrocarbons having an aromatic hydrocarbon purity of greater than 98 liquid volume percent.

It is well known in the prior art that the conventional scheme for synthesizing and purifying C₈ aromatic hydrocarbons from a naphtha utilizes a reforming system and some form of an extraction device for bulk removal of aromatic followed by fractionation facilities to obtain high-purity C₈ aromatic hydrocarbons and particularly the pure xylenes.

I have found that it is possible to produce a mixture of high-purity C₈ aromatic hydrocarbons by processing a naphtha utilizing my flow scheme which includes the steps of prefractionation, catalytic reforming and postfractionation. I have further found that by utilizing a particular prefractionation step and by operating the reforming zone at a severity particular to the fractionated naphtha qualities and by postfractionation of the reformat, a stream of high-purity C₈ aromatic hydrocarbons (para-xylenes, meta-xylenes, ortho-xylenes and ethylbenzene) with an aromatic purity of greater than 98 liquid volume percent at a xylene recovery of approximately 90 liquid volume percent, based on reformat, may be produced.

SUMMARY OF THE INVENTION

Accordingly, it is an object of this invention to provide a process for producing a mixture of high-purity C₈ aromatic hydrocarbons.

It is another object of this invention to provide a process for producing a mixture of high-purity C₈ aromatic hydrocarbons in a more facile and economical manner.

It is a further object of this invention to provide a process for producing a mixture of high-purity C₈ aromatic hydrocarbons having an aromatic hydrocarbon purity of greater than 98 liquid volume percent.

Therefore, the present invention provides a process for producing a mixture of high-purity C₈ aromatic hydrocarbons which comprises the steps of: (a) introducing a C₆-400° F. naphtha feed fraction into a feed splitter prefractionation zone; (b) splitting said fraction into an overhead fraction having a 270° F. to 275° F. end point and a bottoms fraction having a higher end point; endpoint c) introducing said overhead fraction having a 270° endpoint; to 275° F. endpoint into a catalytic reforming zone maintained under reforming conditions sufficient to produce a reformat having a minimum of C₉+ hydrocarbons; (d) passing said reformat into a deoctanizer zone wherein a C₈- hydrocarbon fraction is separated from a C₈+ hydrocarbon fraction; (e) passing said C₈+ hydrocarbon fraction into a rerun column zone wherein a mixture of high-purity C₈ aromatic hydrocarbons is separated from a C₉+ hydrocarbon fraction; and, (f) subsequently recovering said mixture of high-purity C₈ aromatic hydrocarbons.

As will be described hereafter in greater detail, the essence of my invention comprises tying in end point control of the overhead fraction leaving the feed splitter prefractionation zone and the nonaromatic content of the reformat charge to the severity of the reforming operation as measured by the reformat target octane number or the temperature at which the reforming zone is maintained at a given space velocity. I have found that it is necessary to prefractionate the C₆-400° F. naphtha feed fraction into an overhead fraction having a 270° F. to 275° F. end point (ASTM) in order to minimize the concentration of the C₉ paraffins and heavier which, when reformed, produce constituents which boil within the xylene boiling range. It is then necessary to operate the reformer, charging the 270° F. to 275° F. endpoint naphtha at such a severity that sufficient hydrocracking of the naphtha C₉+

material occurs to minimize their final concentration in the reformat.

My invention can be most clearly described and illustrated with reference to the attached drawing which is a schematic representation of a preferred embodiment of my invention.

DESCRIPTION OF THE DRAWING

Referring now to the drawing, a naphtha containing feed is passed via line 1 into crude tower 2 which is a conventional crude tower such as is found in any typical refinery complex.

10 A C₆-400° F. naphtha feed fraction is removed from crude tower 2 via sidcut means 5 via line 6 and passed into a feed splitter prefractionation zone 7. Hydrocarbons lighter than the C₆-400° F. naphtha will be removed from crude tower 2 via line 3 and heavier hydrocarbons removed from tower 2 via line 4.

15 The feed splitter prefractionation zone 7 is operated so that an overhead fraction having a 270° F. to 275° F. endpoint is separated from a bottoms fraction having a higher end point. Typically, the feed splitter will operate at a bottoms temperature of 300° F. to 400° F. and the bottoms fraction is removed from feed splitter 7 via line 8 and passed to a heavy motor fuel reformer (not shown). The overhead fraction having a 270° F. to 275° F. endpoint is passed via line 9 into catalytic reforming zone 25 which is maintained under reforming conditions sufficient to produce a reformat having a minimum of C₉+ hydrocarbon. It has been found that when the overhead fraction having a 270° F. to 275° F. endpoint comprises from 2 to 30 5 liquid volume percent C₉+ naphthenes plus paraffins, the reforming conditions shall include a C₅+ reformat clear target octane of from 92.0 to 96.0. When the overhead fraction having a 270° F. to 275° F. endpoint comprises greater than 10 liquid volume percent C₉+ naphthenes plus paraffins, the reforming conditions shall include a C₅+ reformat clear target octane of greater than 100.0.

35 As will be apparent to one skilled in the art, the reforming zone may contain any suitable reforming catalyst known in the art including those catalysts comprising refractory inorganic oxides such as alumina, which are combined with at least one metal from Group VIII of the Periodic Table and, if desired, a halogen component as well as those reforming catalysts utilizing a crystalline aluminosilicate as the catalyst support. 40 Reforming conditions include a temperature in the range of from 800° F. to 1,100° F. or more, and preferably a temperature in the range of from 850° F. to 1,050° F., and a pressure in the range of from 50 p.s.i.g. to about 1,000 p.s.i.g. or more, and preferably from 100 p.s.i.g. to 1,000 p.s.i.g. The reforming zone may be maintained at a liquid hourly space velocity of 45 0.1 to 20.0 or more, and preferably in the range of from about 0.5 to 15.0 or more, and a gaseous liquid hourly space velocity in the range of from 100 to about 3,000 or more. It is further apparent to one skilled in the art that the 270° F. to 275° F. endpoint overhead feed fraction may be passed through the reforming zone in an upward, downward or radial manner.

50 The reformat passes from reforming zone 10 via line 11 into a deoctanizer zone 12 wherein a C₈ naphthene and lighter hydrocarbon fraction is separated from a C₈ aromatic and heavier hydrocarbon fraction. The deoctanizer may be a conventional fractional distillation column and is usually maintained at a pressure of about 80 p.s.i.g. and a bottoms temperature of from about 300° F. to about 350° F. The top temperature is maintained in the range of from about 200° F. to 55 about 300° F. The C₈ naphthene and lighter hydrocarbon fraction is passed from deoctanizer 12 via line 13 to a motor fuel blending facility (not shown). The C₈ aromatic and heavier hydrocarbon fraction is then passed from deoctanizer 12 via line 14 into a rerun column zone 15 wherein a mixture of high-purity C₈ aromatic hydrocarbons is separated from a C₉+ hydrocarbon fraction. In the drawing, the high purity C₈ aromatic hydrocarbons are represented as being removed from the rerun column via line 17. The C₉+ hydrocarbon fraction is 60 removed from the rerun column via line 16. C₉+ hydrocarbon 65 70 75

fraction is removed from the rerun column via line 16. C₈+ fractions find use as a heavy aromatic solvent and may be utilized for motor fuel blending.

It is also contemplated within the scope of this invention that feed treating means (not shown) be placed in such a manner that, for example, the C₆-400° F. naphtha feed fraction passing via line 6 into feed splitter prefractionation zone 7 be passed through the treating zone for removal of various impurities that may be present. Further, a feed treating zone may also be located in line 9 between the feed splitter prefractionation zone and the reforming zone for removal of impurities from this fraction prior to the fraction passing into the catalytic reforming zone. Feed compound impurities that may be removed include sulfur compound impurities, nitrogen compound impurities, oxygenated compound impurities, and heavy metal impurities that may be present in a conventional naphtha feed.

PREFERRED EMBODIMENT

In a particularly preferred embodiment of my invention, this invention provides a process for producing a mixture of high-purity C₈ aromatic hydrocarbons having an aromatic hydrocarbon purity of greater than 98 liquid volume percent which comprises the steps of: (a) introducing a sidecut fraction from a crude unit distillation column comprising a C₆-400° F. naphtha into a treating zone containing a means for removing sulfur and nitrogen compound impurities from said fraction; (b) removing from said treating zone a treated C₆-400° F. naphtha feed fraction and introducing said fraction into a feed splitter prefractionation zone; (c) introducing said overhead fraction having a 270° F. to 275° F. endpoint into a catalytic reforming zone maintained under reforming conditions sufficient to produce a reformate having a minimum of C₉+ hydrocarbon; (d) passing said reformate into a deoctanizer 35 zone wherein a C₈- hydrocarbon fraction is separated from a stabilized C₈+ aromatic hydrocarbon fraction; (e) passing said stabilized C₈+ aromatic hydrocarbon fraction into a rerun column zone wherein a mixture of high-purity C₈ aromatic hydrocarbons having an aromatic hydrocarbon purity of greater than 98 liquid volume percent is separated from a C₉+ aromatic hydrocarbon fraction; and, (f) subsequently recovering said mixture of high-purity C₈ aromatic hydrocarbons.

It is apparent that the present invention provides a process for producing a mixture of C₈ aromatic hydrocarbons utilizing a process comprising fractionation and catalytic reforming ex-

clusive of extraction. It was found that it was essential to prefractionate the reformate charge to at most 270° F. to 275° F. endpoint (ASTM) inasmuch as experimentation showed that reformates with a clear target octane of 94 to 102 which were produced from naphthas with an end point of 275° F. to 280° F., when fractionated to separate a 275° F.-297° F. xylene heartcut, yielded C₈ aromatic hydrocarbon purities of less than 94 percent and purities as low as 88 liquid volume C₈ aromatic hydrocarbons.

10 I claim as my invention:

1. A process for producing a mixture of C₈ aromatic hydrocarbons having an aromatic hydrocarbon purity of greater than 98 liquid volume percent by fractional distillation and catalytic reforming, exclusive of extraction, which comprises the steps of:

- a. catalytically reforming a naphtha fraction having an end point of 270° to 275° F. and containing from 2 to 10 liquid volume percent C₉+ naphthenes plus paraffins at reforming conditions, sufficient to minimize concentration of C₉+ material in the reformate, including a severity determined as follows:
  - i. for a naphtha containing from 2 to 5 liquid volume percent C₉+ naphthenes plus paraffins, a C₅+ reformate clear target octane of from 92.0 to 96.0;
  - ii. for a naphtha containing from 5 to 10 liquid volume percent C₉+ naphthenes plus paraffins, a C₅+ reformate clear target octane of from 96.0 to 100.0;
- b. separating the resultant reformate by fractional distillation into a C₈- fraction and a C₈- fraction;
- c. separating said C₈- fraction by fractional distillation into a C₉+ hydrocarbon fraction and a C₈ aromatic hydrocarbon fraction having an aromatic hydrocarbon purity of greater than 98 liquid volume percent; and
- d. recovering the last-mentioned fraction as the product of said process.

2. The process according to claim 1 wherein said naphtha fraction having a 270° F. to 275° F. endpoint comprises from 2 to 5 liquid volume percent C₉+ naphthenes plus paraffins and wherein said reforming conditions include a severity producing C₅+ reformate clear target octane of from 92.0 to 96.0.

3. The process according to claim 1 wherein said naphtha fraction having a 270° F. to 275° F. endpoint comprises from 5 to 10 liquid volume percent C₉+ naphthenes plus paraffins and wherein said reforming conditions include a severity producing C₅+ reformate clear target octane of from 96.0 to 100.0.
